MEMO PAD HOLDER

Ira Saltz, Greenlawn, N.Y., assignor to Oxford
Pendaflex Corporation, Garden City, N.Y.

Filed Sept. 28, 1972, Ser. No. 295,991

Term of patent 14 years

Int. Cl. D19—02

U.S. Cl. D74—1 C

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of a memo pad holder showing my new design in transparent form;

FIG. 2 is a top plan view thereof;

FIG. 3 is a right side elevational view;

FIG. 4 is a front elevational view;

FIG. 5 is a rear elevational view;

FIG. 6 is a bottom plan view;

FIG. 7 is a perspective view of the memo pad holder shown in opaque form;

FIG. 8 is a top plan view thereof;

FIG. 9 is a right side elevational view;

FIG. 10 is a front elevational view;

FIG. 11 is a rear elevational view; and

FIG. 12 is a bottom plan view.

I claim:

The ornamental design for a memo pad holder, as shown and described.
